UNITED STATES PATENT OFFICE.

KARL JOHAN GERHARD AHLSTRAND, OF STOCKHOLM, SWEDEN.

VARIABLE CONDENSER FOR TUNING ELECTRIC OSCILLATING CIRCUITS.

Application filed May 4, 1926, Serial No. 106,675, and in Sweden November 13, 1925.

The present invention relates to improvements in variable condensers for tuning electric oscillating circuits in which the rotatable spindle supporting the movable plates and a fine tuning spindle are connected to each other by means of a gearing device consisting of a wheel journalled on an eccentric which is supported by the fine tuning spindle and is in frictional engagement with a casing surrounding said wheel and being secured to the spindle supporting the movable plates. Variable condensers having such a gearing device are described in my co-pending application Serial No. 54,022, filed September 2nd, 1925.

The object of my present invention is to make the said gearing device variable and at the same time to simplify the device used for guiding the wheel journalled on the eccentric.

The invention consists, chiefly, in this that the eccentric is movable in radial direction whereby it is possible to change the relation between the circumference of the wheel and the circular path of engagement of the casing surrounding said wheel and thus the ratio of gear between the two spindles.

In the accompanying drawing I have shown one embodiment of my invention.

Fig. 1 shows an end view of a condenser, the gearing device being shown in section on line *a*—*b* of Fig. 2, and

Fig. 2 shows a horizontal section on line *c*—*d* of Fig. 1.

Referring to the drawing, 1 indicates the frame to which the fixed plates 1^a of the condenser are secured. 2 indicates a rotatable spindle supporting the movable plates 2^a of the condenser. To the rear end of said spindle is secured the one part 3 of a casing 3, 4, the circumferential portion of which is of wedge-shaped cross-section, as is clearly shown in Fig. 2. The two parts 3, 4 of which the casing is composed may be connected to each other, for instance, by threaded flanges 3^a and 4^a respectively, so that the distance between the walls of the casing may be varied.

The spindle 2 is hollow and in the same is rotatably journalled a fine tuning spindle 5 supporting an eccentric which in the construction form shown consists of a wire 6¹ of steel or other yielding material protruding a distance from the axle 5. The said

wire 6¹ is disposed in a longitudinal groove 16 in the spindle 5 and is at its inner end rigidly secured to the spindle, for instance, by soldering. The wire is so arranged that its free end tends to move radially outwards from the groove 16. The wheel 7 is disposed on the end of the wire 6¹ extending into the casing 3, 4. Said wheel consists of a solid disc of metal or other suitable material and to the same an arm 8¹ is secured which extends through a slot 17 in the bottom 3 of the casing and is provided at its free end with a notch 12¹ engaged by a pin 13¹ secured to the frame 1. The spindle 2 supports a hand wheel 14 and the spindle 5 a knob 15.

The device works as follows. The wheel 7 is pressed by the wire 6¹ into engagement with the walls of the casing 3, 4, two opposite points of the edges of the wheel 7 engaging the conical portions of the walls of the said casing. By suitable choice of the pressure exerted by the wire 6¹ a suitable friction between the wheel and the casing is obtained. When the spindle 5 is rotated, the edges of the wheel will engage successively different points of the walls of the casing, i. e. the circumference of the wheel will roll off itself along a circular path in the casing, the diameter of which is determined by the thickness of the wheel 7 and the distance between the conical walls of the casing 3, 4. This path is indicated in Fig. 1 by the dotted line 18. As the wheel 7 is in connection with the fixed frame 1 through the arm 8¹, it will impart to the casing and the spindle 2 connected thereto a rotary motion the size of which is determined by the difference between the circular path 18 and the circumference of the wheel 7. In the present case it is, however, possible to change the size of the path 18. This can be done by screwing the cover 4 more or less towards the bottom 3, whereby the distance between the conical side walls 100 will be changed. This in its turn is possible by the eccentric 6¹ being disposed yieldingly so that the eccentricity accommodates itself to the path of engagement for which the casing has been regulated. In this way 105 every desired ratio of gear between nil and the maximum ratio of gear determined by the dimensions of the device may be obtained.

In the construction form shown the wheel 110

7 is guided by the arm 8¹ only and will on account thereof when being moved by the eccentric make a small oscillatory rotating movement around its centre. The size of this movement depends on the length of the arm 8¹ and as a result of said movement the ratio of gear between the spindles 2 and 5 is changed continually during each revolution of the spindle 5. When the wheel 7 is in the position shown in the drawing, i. e. when the point of engagement between the wheel and the casing is nearest to the pin 13¹, the ratio of gear is smallest. From this point it increases continually during half a revolution until said point of engagement has moved to the opposite end position and thus is at the greatest distance from said pin 13. During the following half revolution the ratio of gear decreases continually until it at last when the revolution is completed and the wheel 7 has returned into its initial position has been reduced to its original value. Said variations of the ratio of gear which may be reduced by increasing the length of the arm 8¹ are in many cases of no practical importance, but obviously it is desirable to be able to obviate the same, if this can be done in a simple manner. In the present case this is possible without complicating the device in any way and without introducing any new elements simply by placing the hole of the wheel 7 engaged by the eccentric 6¹ not in the centre of the wheel but slightly nearer to the guiding pin 13¹ or that point of engagement of the wheel that gives the slowest ratio of gear. Hereby a wheel 7 is obtained the radius of which counting to the point of engagement increases continually during half a revolution of the spindle 5 from the position shown in the drawing and decreases continually in the same proportion during the following half revolution of said spindle 5. Thus the same result is reached as if there were used in each new point of engagement a wheel having another circumference than that used in the foregoing point of engagement. As the path 18 remains the same, a variation of the ratio of gear is obtained which is contrary to the variation of the ratio of gear caused by the arm 8¹. By suitable choice of the position of the hole of the wheel 7 said variations can be made the same in size and thus compensate each other so that a quite uniform ratio of gear between the two spindles 5 and 2 is obtained.

Obviously the device described above may be varied as to their details without deviating from the principle of the invention.

Having now described my invention what I claim is:

1. In a variable condenser for tuning electric oscillating circuits the combination of a system of fixed plates, a system of movable plates, a spindle supporting the said movable plates, a fine tuning spindle having the same axis of rotation as the first mentioned spindle, a casing on the latter, an eccentric supported by the said fine tuning spindle and being movable radially, a wheel journalled on said eccentric within the said casing and being in frictional engagement therewith, and means for preventing the one of said two members being in frictional engagement from being rotated, substantially as and for the purpose set forth.

2. In a variable condenser for tuning electric oscillating circuits the combination of a system of fixed plates, a system of movable plates, a spindle supporting the said movable plates, a fine tuning spindle having the same axis of rotation as the first-mentioned spindle, a casing on the latter, a wire of yielding material having its one end rigidly secured to the said fine tuning spindle, the other free end of said wire tending to move outwards from the axis of rotation of said fine tuning spindle, a wheel journalled on the free end of the said wire within the said casing and being in frictional engagement therewith, and means for preventing the one of said two members being in frictional engagement from being rotated, substantially as and for the purpose set forth.

3. In a variable condenser for tuning electric oscillating circuits the combination of a system of fixed plates, a system of movable plates, a hollow spindle supporting the said movable plates, a fine tuning spindle rotatably journalled in the said hollow spindle, a casing rigidly secured to the latter in centric relation thereto, a wire of yielding material having its one end rigidly secured to the said fine tuning spindle, the other free end of said wire tending to move outwards from the axis of rotation of said fine tuning spindle, a wheel formed with an eccentrically located hole loosely engaged by the free end of said wire, the said wheel being disposed within said casing in frictional engagement therewith, an arm rigidly secured to said wheel and means for guiding said arm so as to prevent the said wheel from being rotated, substantially as and for the purpose set forth.

In testimony whereof I have hereunto subscribed my name.

KARL JOHAN GERHARD AHLSTRAND.
